(57) **CLAIM**

I claim the ornamental design of a label, as shown and described.

DESCRIPTION

FIG. 1 is a top plan view of a first embodiment of a label showing our new design, the side and bottom views thereof being disclaimed and, therefore, not shown; and,

FIG. 2. is an enlarged fragmentary top plan view of the label of FIG. 1, showing the label in greater detail.

Features shown in broken lines show environmental structure and form no part of the claimed design.

The Gerolsteiner logo forming part of the claimed design is a registered trademark owned by Gerolsteiner Brunnen GmbH & Co. KG.
